UNITED STATES PATENT OFFICE.

CHARLES O. MICHAELSEN, OF OMAHA, NEBRASKA.

ORE-CLASSIFIER.

1,090,326.

Specification of Letters Patent. Patented Mar. 17, 1914.

Application filed June 25, 1912. Serial No. 705,858

To all whom it may concern:

Be it known that I, CHARLES O. MICHAELSEN, a citizen of the United States, and a resident of Omaha, in the county of Douglas and State of Nebraska, have invented certain new and useful Improvements in Ore-Classifiers, of which the following is a specification.

My invention relates to screening and separating machines, and it is the object of my invention to provide an efficient and economical mechanism for screening and classifying crushed or pulverized ores, especially where the crushed or pulverized material is handled while mixed with a sufficient volume of water to make it substantially fluid.

Further objects of my invention will be fully set forth in the following description.

In the accompanying drawings, Figure 1 is a longitudinal sectional view of a classifier embodying my invention; Fig. 2 is a section on the plane of the line $x-x$ of Fig. 1, showing the driving gear, Fig. 3 is a detail longitudinal section showing some of the parts on a larger scale than in Fig. 1, Figs. 4 and 5 are side and end views, respectively, of one of the screen-frames, and Fig. 6 is a detail section through the edge of one of the screen-frames.

In carrying out my invention I provide a tubular shaft 1 which is revolvably mounted in suitable bearings 2, said bearings being disposed on standards 3, 4 and 5 so that the shaft is inclined slightly from a horizontal position. The said standards are preferably supported upon masonry foundations, as shown. In the upper part of the standards 4 and 5 is journaled a shaft 6, on the ends of which are carried the drive-pulleys 7. On the central part of said shaft is a gear 8 which meshes with a gear 9 mounted on a shaft 10 which is also journaled in bearings on the standards 4 and 5. The gear 9 meshes with a gear 11 mounted concentrically with the shaft 1, the said gear being yieldably connected with a hub-body 12 secured to the shaft. To the hub-body is adjustably secured a plate 13 which carries at its outer edge rollers 14 adapted to engage similar rollers 15 mounted on a plate 16 which is adjustably secured to the gear 9. The shaft 6 being driven at a uniform speed imparts a like motion to the gears 8, 9 and 11, but the movement of the hub-body 12 and shaft 1 is intermittently retarded by the interference of the rollers 15 and 16, the

variation of movement between the gear 11 and hub-body 12 being permitted by the yieldable connection thereof, as fully set forth in my pending application for patent 60 on interrupted-drive gearing, filed August 3, 1911, Serial No. 642,216. The shaft 1 is thus given an intermittent or alternately retarded and accelerated movement.

Upon the shaft 1 near the bearing carried by the standard 4 is a circular peripherally-flanged plate 17 having a central hub-portion which fits around and is secured to the shaft. The said plate supports and closes one end of a cylinder 18 arranged concentrically with the shaft. The other end of the cylinder is open and is supported and connected with the shaft by a spider 19. Similar spiders 20 and 21 carry rings 22 and 23, respectively, axially alined with the cylinder. Upon said rings 22 and 23, and upon the cylinder 18 adjoining the open end thereof, are secured flange-rings 24 which are arranged so as to form annular wedge-shaped channels at the adjacent ends of the 80 rings and cylinder. Ribbed transversely curved rectangular frames 25 are provided, of which the end portions 26 have the form of beveled ring-segments adapted to fit into the annular channels beneath the flange-rings 24. Along the longitudinal edges of each frame at one side is a tongue 27 and at the other a channel or rabbet 28, into which the tongue of the adjoining frame fits to form a lap-joint at the adjoining edges of 90 the frames, as shown in Fig. 5. At intervals along the longitudinal edges of the frames at the inner sides thereof, are lugs 29 and in the inner edges of said lugs are formed channels adapted to receive the edges 95 of the screens 30. The said edges of the screens are preferably covered with binding-strips 31, U-shaped in section, as shown in Fig. 6, and one or more reinforcing-strips 32 may be extended across the central part 100 of the screens, on the inside thereof and secured thereto, as shown in Fig. 4. The screens may be removed from or placed in the frames by merely sliding them longitudinally through the channels in the lugs 29. 105 By this means of securing the screens the same are held so as to form a practically continuous sheet or layer coincident with the inner sides of the frames. Two sets of the screen-frames are employed, the one forming a cylindrical inclosure for the space between the end of the cylinder 18 and the

ring 22, or being in effect a continuation of the cylinder 18, and the other similarly enclosing the space between the rings 22 and 23. The insertion of the end portions 26 of the screen-frames into the annular channels beneath the flange-rings 24, and their removal therefrom, is permitted by sliding the spiders 20 and 21 longitudinally upon the shaft 1.

10 Adjacent to the spider 21 and ring 23 a circular plate 33 is disposed, being slidably connected with the shaft 1 by means of a collar 34. Adjoining the bearing 2 carried by the standard 3 is a thrust-bearing 35 for receiving the end-thrust of the shaft due to its inclination toward this end of the machine.

15 The material to be screened, together with a sufficient volume of water to cause it to flow readily, is fed into a hopper 36 arranged at the upper end of the shaft 1. From the hopper a feed pipe 37 extends into the tubular shaft, passing through a plate 38 fixedly connected with the end of the bearing 2 on the standard 5. Ports 39 are made through the sides of the shaft just within the closed end of the cylinder 18 adjoining the end-plate 17, and a plug 40 is placed in the bore of the shaft near said ports to prevent the material from the feed pipe passing on down the shaft beyond the ports 39. The material from the feed pipe passes through the ports 39 into a substantially closed chamber 50 formed between the end-plate 17, the cylinder walls, and a plate 41 which is slidably secured on the shaft adjacent to the end-plate 17. The size of the plate 41 is such as to leave a narrow annular opening between its edge and the cylinder walls, and through said opening the material from the chamber 50 escapes in a thin sheet or stream.

20 Secured to the standard 3 adjoining the shaft-bearing thereon, is a casing 42 of which the outer end fits around a pipe 43 and is clamped thereon by bolts 44. The pipe 43 passes through a packing gland 45 disposed in the end of the shaft 1 and extends for some distance into the shaft, as shown in Fig. 1. The outer end of the pipe 43 is connected with a suitable water supply. The water admitted to the tubular shaft through the pipe 43 escapes from the shaft through ports 46 made therein at the position shown. Slidably secured upon the shaft at each side of the ports 46 are the hollow conical water distributers 47 and 48, the first of which is larger than the latter and is disposed with its mouth or larger end toward the lower end of the screen-cylinder. The smaller cone 48 is disposed within the other, with its mouth directed oppositely thereto, and is adjusted to a position such that a narrow annular opening is left between its edge and the inner surface of the

25 larger cone. Through said opening the water from the ports 46 passes in a thin sheet or stream which flows down the inner surface of the cone 47, being thereby directed onto the inner surface of the screen-cylinder at or near the ring 22. The place at which the water is discharged may be varied more or less by moving the cones 47 and 48 longitudinally of the shaft, as shown by the positions thereof in full and dotted lines in Fig. 3. The width of the annular opening around the edge of the cone 48 may also be varied by changing the longitudinal relation of the cones.

30 It may be noted that, for convenience of construction, the end-plate 17, the plate 41, the spiders 19, 20 and 21, the cones 47 and 48, and the collar 34 of the plate 33, are all prevented from rotation relative to the shaft 1 by means of a spline 49 set in the shaft 35 and extending through all of the parts named. Each of said parts is also provided with set-screws for normally preventing movement thereof longitudinally of the shaft. Where both the shaft and the parts 30 disposed thereon are of steel or iron so that by rusting they might adhere to each other and prevent the parts being readily moved upon the shaft, it is preferable to place a bushing 51 of bronze or similar material 35 within the bore of each of the parts between it and the shaft.

35 Receiving troughs 52 are disposed below the screens, there being shown in the drawing one trough for each of the screen portions between the circumferential ribs of the screen-frames, and an additional trough 53 below the discharge-opening between the ring 23 and the plate 33. Screens of different mesh may be employed for each of the 40 said circumferential portions between the frame-ribs, so that a number of gradations of the material may be made in a single operation thereon. The total screen area may be varied by employing screen-frames of different length, sliding the rings 22 and 23 along the shaft so as to accommodate them.

45 In the operation of the machine the intermittent rotary motion given to the screen-cylinder by the driving mechanism causes a surging and scouring action of the materials circumferentially of the cylinder. The material is carried longitudinally of the cylinder partly by the flow of the water with which it is mixed when fed into the machine, and partly by its tendency to pass in a helical path around the cylinder, due to the rotation thereof and its inclined position. Most of the water originally mixed with the material will pass through the screen portions between the end of the cylinder 18 and ring 22, carrying with it the material small enough to pass said portions of the screen. The material which has passed across the first part of the screen then re-

ceives a fresh supply of water furnished through the pipe 43 and ports 46, and distributed by the cones 47 and 48. The water thus supplied is of considerable assistance in carrying the material through and across the second screen-portion, or that between the rings 22 and 23.

Now, having described my invention, what I claim and desire to secure by Letters

10 Patent is:

1. In a machine of the class described, a revoluble shaft, a cylinder mounted thereon and having an open end, cylindrical screens forming a continuation of the cylinder beyond the open end thereof, means for feeding water and the material to be screened into the cylinder, and means for distributing water onto materials which have passed across a portion of the screens, said means comprising a pair of conical members slid- 15 able on the shaft and having an annular opening between them.

2. In a machine of the class described, a revoluble shaft, a cylindrical screen mounted thereon concentrically therewith, means for feeding water and materials to be screened into one end of the cylindrical screen, and means for distributing water onto materials which have passed over a part of the screen, said means comprising a conical member secured upon the shaft and extending adjacent to the screen surface, and means for supplying water upon the inner surface of said conical member.

3. In a machine of the class described, a revoluble shaft, rings slidably mounted thereon, means forming annular channels in the adjacent sides of the rings, and screen-frames having end-portions adapted to enter 35 said channels, and removable therefrom by movement longitudinally of the shaft.

4. In a machine of the class described, a cylindrical screen comprising series of rectangular transversely curved integral screen-frames, means for holding said frames with the longitudinal edges thereof in contact, lugs at the inner longitudinal edges of the frames, said lugs having longitudinally extending channels therein, and screens having their longitudinal edges slidably disposed in 50 said channels.

5. In a machine of the class described, a tubular revoluble shaft, a cylindrical screen mounted upon the shaft, means for feeding materials onto the screen, means for admitting water into the tubular shaft, the shaft having ports for the discharge of the water therefrom, and hollow cones slidably disposed on the shaft at each side of the ports and having an annular opening between 55 them, one cone extending into proximity to the screen for the purpose set forth.

6. In a machine of the class described, a revoluble shaft, spiders slidably mounted thereon, rings secured on said spiders concentrically with the shaft, means forming annular channels in the adjacent sides of the rings, screen-frames having end-portions adapted to enter the channels and removable therefrom by movement longitudinally of the shaft, and means for retaining screens in longitudinally slidable engagement with the inner surfaces of the screen-frames.

In testimony whereof I have hereunto sub- 75 scribed my name in the presence of two witnesses.

CHAS. O. MICHAELSEN.
